DESIGN FOR AN ALPHABET FOR FORMING MONOGRAMS OR THE LIKE

Michael Chernow, Providence, R. I.

Application October 21, 1936, Serial No. 65,412

Term of patent 7 years

To all whom it may concern:

Be it known that I, Michael Chernow, a citizen of the United States, and residing at Providence, in the county of Providence and State of Rhode Island, have invented a new, original, and ornamental Design for an Alphabet for Forming Monograms or the like, of which the following is a specification, reference being had to the accompanying drawing, forming part hereof, and in which

Fig. 1 is a view of the alphabet showing my new design,

Fig. 2 is a perspective view showing one of the letters of the alphabet.

The characteristic feature of the alphabet resides in the enlarged rounded bottoms of the characters.

I claim:

The ornamental design for an alphabet for forming monograms or the like, substantially as shown, and described.

MICHAEL CHERNOW.
